[57]**CLAIM**

I claim the ornamental design for an egg carton for eggs and other ingredients, as shown and described.

DESCRIPTION

FIG. 1 is a perspective view of an egg carton for eggs and other ingredients showing my new design;
 FIG. 2 is a top plan view thereof the bottom plan view being identical;
 FIG. 3 is an end elevational view thereof, the opposite end being a mirror image thereof;
 FIG. 4 is a front side elevational view thereof; and,
 FIG. 5 is a rear side elevational view thereof.

1 Claim, 2 Drawing Sheets
